US00D628631S

(12) **United States Design Patent**
Liu

(10) **Patent No.:** **US D628,631 S**
(45) **Date of Patent:** **** Dec. 7, 2010**

(54) **MARKER**

(75) Inventor: **Luosen Liu**, Ningbo (CN)

(73) Assignee: **Beifa Group Co., Ltd.**, Ningbo (CN)

(**) Term: **14 Years**

(21) Appl. No.: **29/357,386**

(22) Filed: **Mar. 11, 2010**

(30) **Foreign Application Priority Data**

Sep. 11, 2009 (CN) 2009 3 0208058

(51) **LOC (9) Cl.** **19-06**

(52) **U.S. Cl.** **D19/41**

(58) **Field of Classification Search** D19/35,

(57) **CLAIM**

The ornamental design for a marker, as shown and described.

DESCRIPTION

FIG. 1 is an upper front right perspective view of a marker showing my new design;

FIG. 2 is a lower front left perspective view thereof;

FIG. 3 is a front elevation view thereof;

FIG. 4 is a right side elevation view thereof, with the left side elevation view being a mirror image of the right side elevation view;

FIG. 5 is a rear elevation view thereof;

FIG. 6 is an enlarged top plan view thereof; and,

FIG. 7 is an enlarged bottom plan view thereof.

The feature shown in broken lines on the top of the marker in FIGS. 1 and 6 is included for the purpose of illustrating environment and forms no part of the claimed design.

1 Claim, 3 Drawing Sheets
